(57) **CLAIM**

We claim the ornamental design for a “vessel for electrochemical treatment,” as shown and described.

DESCRIPTION

FIG. 1 is a top right perspective view of a vessel for electrochemical treatment;

FIG. 2 is a top view of the vessel of FIG. 1;

FIG. 3 is a bottom view of the vessel of FIG. 1;

FIG. 4 is a second top right perspective view of the vessel of FIG. 1;

FIG. 5 is a right view of the vessel of FIG. 1;

FIG. 6 is a right cross sectional view of the vessel of FIG. 1;

FIG. 7 is a left view of the vessel of FIG. 1;

FIG. 8 is a left cross sectional view of the vessel of FIG. 1;

FIG. 9 is a front view of the vessel of FIG. 1;

FIG. 10 is a front right perspective cross sectional view of the vessel of FIG. 1;

FIG. 11 is a front left perspective cross sectional view of the vessel of FIG. 1;

FIG. 12 is a bottom right perspective view of the vessel of FIG. 1;

FIG. 13 is a bottom left perspective view of the vessel of FIG. 1;

FIG. 14 is a back view of the vessel of FIG. 1; and,

FIG. 15 is a back right perspective cross sectional view of the vessel of FIG. 1.
